UNITED STATES PATENT OFFICE

HARRY M. FARRAND, OF LOS ANGELES, CALIFORNIA

DESIGN FOR A COMBINED RADIO RECEIVER CABINET AND CLOCK

Application filed January 17, 1930. Serial No. 34,170. Term of patent 3½ years.

To all whom it may concern:

Be it known that I, HARRY M. FARRAND, a citizen of the United States, residing in the city of Los Angeles and State of California, have invented a new, original, and ornamental Design for a Combined Radio Receiver Cabinet and Clock, of which the following is a specification, reference being made to the accompanying drawing, forming part thereof.

Fig. 1 is a front elevation of a combined radio receiver cabinet and clock, showing my new design.

Fig. 2 is a side elevation thereof.

I claim:

The ornamental design for a combined radio receiver cabinet and clock, substantially as shown.

HARRY M. FARRAND.
